[57] CLAIM

The ornamental design for a combined lamp and flower holder, as shown and described.

DESCRIPTION

FIG. 1 is front perspective view of a combined lamp and flower holder showing my new design;

FIG. 2 is a side elevational view showing my new design;

FIG. 3 is a top view thereof; and,

FIG. 4 is a bottom view thereof.

The broken line showings of a lamp shade, shade holder, bulb, socket, cord and flowers are for illustrative purposes only and forms no part of the claimed design.
